UNITED STATES PATENT OFFICE.

JAMES F. MARTIN, OF PHILADELPHIA, PENNSYLVANIA, ASSIGNOR TO JOHN B. HALL, OF PHILADELPHIA, PENNSYLVANIA.

HAIR-CRIMPER.

SPECIFICATION forming part of Letters Patent No. 710,702, dated October 7, 1902.

Application filed June 26, 1902. Serial No. 113,297. (No model.)

To all whom it may concern:

Be it known that I, JAMES F. MARTIN, a citizen of the United States, residing at Philadelphia, in the county of Philadelphia and State 5 of Pennsylvania, have invented a certain new and useful Hair-Crimper, of which the following is a specification.

My invention relates to that class of hair-crimpers in which two or more jaws are secured together at one of their ends in such manner as to be movable with reference to each other; and the principal objects are to provide suitable means for connecting the jaws, whereby the vexatious pulling or catching 15 of the hair will be wholly avoided, and to provide a quick and efficient interlock for the free ends of the jaws which will be positive against accidental movement of the jaws in all directions. The objects thus stated, the 20 invention comprises the improvements hereinafter described and claimed.

The nature, characteristic features, and scope of the invention will be more fully understood from the following description, taken 25 in connection with the accompanying drawings, forming part hereof, and in which—

Figure 1 is a perspective view of a hair-crimper embodying features of the invention, showing the same in closed position. Fig. 2 30 is a longitudinal sectional view of the same. Fig. 3 is a similar view with hair applied to the crimper, illustrating how the jaws are positively locked against accidental movement in all directions; and Fig. 4 is a view 35 illustrating the crimper in open position.

In the drawings, 1 and 2 are jaws or strips connected together at one of their ends, so as to be movable in respect to each other, and for this purpose use is made of the hinge or 40 eyelet 3, because it does not catch or pull the hair, as does the usual pivot-pin or rivet, and is far more attractive looking, not to mention the fact that it exerts less friction on the parts and that consequently there is much 45 less wear. These jaws or strips may be made of any appropriate material, as metal, celluloid, or any variety of materials too numerous to mention, and, if desirable, they may be covered with fabric or the like. One of

the jaws has its free end served with an overhanging projection or lip 4, which forms a part of or may be applied thereto, and said projection or lip is provided with a somewhat-elongated concavity or depression 5, adapted to engage with a complementary projection or 55 hump 6 on the free end of the other jaw, and said parts constitute a simple and efficient interlock for securing the jaws in their closed position. The jaws are not only locked against accidental lateral movement, but are, 60 as graphically shown in Fig. 3, locked against accidental movement in all directions. In use these jaws or strips are opened in respect to each other and a strand or strands of hair is or are wound around and between them. 65 They are then closed in respect to each other by causing the parts 5 and 6 to interlock and serve to keep the hair in position until it becomes crimped. Of course the catch or interlock may be differently or elsewhere located than as stated—for instance, by forming or applying its respective parts to the sides of the jaws 1 and 2 instead of at their ends. 70

It will be obvious to those skilled in the art 75 to which the invention relates that modifications may be made in details without departing from the spirit thereof. Hence I do not limit myself to the precise construction and arrangement of parts hereinabove set forth 80 and illustrated in the accompanying drawings; but,

Having thus described the nature and objects of the invention, what I claim as new, and desire to secure by Letters Patent, is— 85

1. A hair-crimper comprising jaws or strips movably connected at one of their ends and whereof one of said jaws is provided with a projection adapted and arranged to engage with a complementary depression on the other 90 jaw, whereby accidental movement of the jaws in all directions is prevented.

2. A hair-crimper comprising jaws or strips movably connected at one of their ends, one of said jaws being provided with an overhanging projection or lip having a depression and the free end of another jaw having a complementary projection adapted and ar- 95

ranged to engage with said depression, whereby accidental movement of the jaws in all directions is prevented.

3. A hair-crimper comprising a pair of flat jaws or strips, an eyelet pivotally connecting said jaws or strips at one extremity of the pair, one of said jaws being provided with an overhanging projection or lip having a depression, and the free end of the other jaw ⁵ having a complementary projection adapted ¹⁰ to engage with said depression, whereby accidental movement of the jaws in all directions is prevented.

and arranged to engage with said depression, whereby accidental movement of the jaws in all directions is prevented.

In testimony whereof I have hereunto signed my name.

JAMES F. MARTIN.

In presence of—

GILBERT RESIN,
JAMES A. STEAD.
